UNITED STATES PATENT OFFICE

NESTOR LÉONARD, OF FEIGMIES, FRANCE

CAST FRAME FOR RAILWAY ROLLING STOCK

Application filed August 16, 1928, Serial No. 299,894, and in France November 21, 1927.

My invention relates to castings of large dimensions and particularly frames for railway rolling stock.

Castings of large dimensions, particularly 5 profiled pieces in cast steel present cheeks and partitions transverse relatively to such pieces and therefore involving transverse intersections, i. e. located in a plane perpendicular to the large length of such pieces.

10 These transverse intersections are the cause of cracks and rents in the metal. If in fact, a casting 1 of large dimensions is poured (Figs. 1 and 2) having transverse vertical lugs 2¹, 2², and thus involving transverse intersections 3¹, 3², the molding sand between the lugs 2¹, 2², offers a considerable resistance at the instant of solidification of the metal. Such solidification entails in fact a shrinkage 15 of 20 millimetres per metre, that is to say that the lugs 2¹, 2², if they were separated by one metre at the instant of pouring, are located at a distance of only .980 metre apart after the solidification of the metal.

The sand, compressed between the lugs, 20 exerts therefore forces in the directions P¹, P² against the lugs at an instant when the transverse intersections 3¹, 3² having much larger thicknesses of metal still comprise metal more or less pasty, i.e. not yet solidified. Such metal cannot therefore resist the molecular tensions of the other already cooled and solidified parts of the casting 1, nor the pressure exerted on the lugs by the forces P¹, P² of the compressed sand. Cracks or rents 30 therefore arise at the transverse intersections 3¹, 3².

The present invention has for its object the elimination of the above indicated disadvantages.

40 The invention relates firstly to a casting of large dimensions, profiled or not, the feature of which is that the cheeks or lugs are produced by casting with an auxiliary longitudinal partition of small dimensions joining 45 on to one or several flanges of the casting of large dimensions, the shrinkage of the metal of such small longitudinal auxiliary partition being negligible and in consequence occasioning neither cracks nor rents.

50 The invention relates also to a casting of

large dimensions the feature of which is that the supports or other similar accessories cast integral therewith are hollow, by the provision of a core during casting, which enables as far as possible the regulation of the thicknesses and avoids any intersection provocative of rents or cracks in the casting of large dimensions. 55

The invention also involves other features hereinafter described and to their various 60 applications.

Castings according to the invention are illustrated by way of example on the accompanying drawings, in which:—

Figs. 1 and 2 are respectively a longitudinal 65 and transverse section of a portion of a casting produced by the old method.

Fig. 3^a is a longitudinal section of a portion of a casting of large dimensions according to the invention, and 70

Fig. 4^a is a transverse section of such casting.

Fig. 3^b is a longitudinal section of a casting according to a modification of the invention, and 75

Fig. 4^b is a transverse section of such casting along the line 4^b—4^b of Fig. 3^b.

Figs. 3^c and 4^c correspond to another modification of the invention, Fig. 4^c being a horizontal section along the line 4^c—4^c of Fig. 80 3^c, and

Fig. 5^b is a vertical transverse section of such casting along the line 5^b—5^b of Fig. 3^c.

Figs. 5 and 5^a are respectively a plan partly 85 in section and elevation of a frame for railway rolling stock according to the invention,

Figures 6 and 6^a are elevations of end portions of the frame, respectively.

Fig. 7 is a section on the line 7—7 of Fig.

5. Figs. 8 and 8^a are sections on the lines 8—8 90 and 8^a—8^a, respectively, of Figs. 5 and 5^a, respectively.

Fig. 9 is a fragmentary transverse section of the frame along the line 9—9 of Fig. 5^a.

Fig. 10 is an elevation of a support for the 95 suspension rod of a brake shoe of the above frame, such support being carried by an end transverse member,

Fig. 11 is a vertical section of such support along the line 11—11 of Fig. 10, and 100

Fig. 12 is a horizontal section of the same support along the line 12—12 of Fig. 11.

Fig. 13 is a horizontal section of the transverse member supporting the brake beams and of the headstock, and

Figs 14 and 15 are two vertical sections of these parts respectively along the lines 14—14 and 15—15 of Fig. 13.

Figs. 16 and 17 are respectively a horizontal section and a vertical section of the transverse member supporting the brake beams and of the intermediate transverse member, and

Fig. 18 is a section of these parts along the line 18—18 of Fig. 16.

Figs. 19 and 20 are respectively a sectional plan and an elevation of a support for the suspension springs,

Fig. 21 is a vertical section of such support along the line 21—21 of Fig. 20, and

Fig. 22 is a horizontal section of such support along the line 22—22 of Fig. 21.

Fig. 23 shows in side elevation a support for a brake rod not shown in the general view Fig. 5, and

Figs. 24 and 25 are two sections of such support respectively along the lines 24—24 and 25—25 of Fig. 23.

Figs. 26 and 27 are respectively an elevation and a plan of a support for a shock absorber spring, and

Fig. 28 is a section of such support along the line 28—28 of Fig. 26.

Figs. 29 and 30 are respectively a plan and an elevation of a support for a brake shoe suspension rod, such support being provided on the intermediate transverse member of the frame, and

Fig. 31 is a vertical section of such support along the line 31—31 of Fig. 29.

The casting 1 of large dimensions (Figs. 3^a and 4^a) of channel cross section has two lugs 2¹, 2² for the articulation of any appropriate accessory member. These lugs are

produced in casting with auxiliary partitions 7¹, 7² of small dimensions, these partitions which extend longitudinally and parallel with the web of the casting 1 join on to the flanges 1¹, 1² of the casting 1 along the longitudinal surfaces 11¹, 11².

The shrinkage of the metal of these small longitudinal auxiliary partitions 7¹, 7² is negligible and in consequence produces neither cracks nor rents. The web of the casting 1 thus remains without any intersection and therefore is of unimpaired uniformity.

Moreover the lugs 2¹, 2² are supported no longer on the web of the casting, but on the small longitudinal auxiliary partition 7¹, 7². Therefore, the pressure withstood by the lugs acts, relatively to their base of attachment, with a far lesser leverage than in castings hitherto wherein the lug intersects the web itself of the casting of large dimensions and

acts on a region wherein the quality of the metal is doubtful.

The longitudinal auxiliary partition 7¹ offers a resistance to tearing off far greater than if the lugs 2¹, 2² were joined transversely to the casting 1 of large dimensions.

Finally, all the auxiliary partitions (7¹, 7²) being longitudinal exert only a much reduced pressure for compressing the sand of the mould; in consequence these partitions are subjected on the part of the mass of sand only to reactions too feeble to produce cracks and rents.

The invention applies to the preceding arrangements whatever be the shape of the casting 1 of large dimensions; in particular the casting 1 instead of being of channel profile as shown in Figs. 3^a and 4^a, may also be a piece of rectangular section. In that case, the small longitudinal auxiliary partition 7 is provided with one or several longitudinal flanges 7^a, 7^b which join on to the casting of large dimensions in such a manner as to constitute a profiled cross section.

The advantages of this arrangement are similar to those of the arrangement shown in Figs. 3^a and 4^a for the same reasons.

In the modification illustrated in Figs. 3^c, 4^c and 5^b, the casting 1 of large dimensions presents a bracket 35 with a lug 36 for holding a spring for example. This bracket cast with the casting 1 of large dimensions is hollow, the interior of the bracket being recessed by providing a core during casting. In consequence such bracket has approximately the same thickness as the web of the longitudinal member; there is therefore no danger of cracks or rents being produced at the base of the bracket, since there is no intersection.

The invention applies to castings of large dimensions as above described, whatever be the nature of such castings; such castings can be for marine, building or other constructional purposes.

However, the invention extends also to the application of the above arrangements to cast steel frames for railway rolling stock, such arrangements in such application presenting particular advantages with a view to strength to withstand the violent shocks to which at times such frames are subjected and with a view to lightness of such frames, which enables their dead weight to be reduced and the desired degree of flexibility to be imparted to them.

It is assumed that the frame of Figs. 5 to 9 comprises a number of accessory members formed by casting with the frame according to the invention.

Figs. 10 to 12 show first a support 5 for a brake shoe suspension rod. Such a support is formed on the end transverse members 6¹, 6² of the frame, in proximity to each corner of the frame (Fig. 5), four such supports being carried by the frame. Each support

5 consists of two ears 5¹, 5² formed by casting with a small longitudinal partition 77 parallel to the web of the respective end transverse member 6, the ends of this small partition merging along the longitudinal lines 11¹, 11² into the flanges 10¹, 10² of the channel section end transverse member 6. This disposition of the small longitudinal partition 77 ensures the advantages explained already with the aid of Figs. 3^a and 4^a, these advantages being particularly emphasized in the case of the bogie frame by reason of the shocks and vibrations to which it is subjected.

Figs. 13 to 15 show the application of the invention to a transverse member 20 supporting the brake beams and belonging to an end transverse member 6¹, 6². The longitudinal member 20 for the brake beam, which has a T cross section (Fig. 15), joins by its upper face to the flange 10² of the end transverse member 6 and by its web to a small longitudinal auxiliary partition 22 joined itself along the horizontal lines 23¹, 23² to the flanges 10¹, 10² of the transverse member 6. Thus an arrangement quite similar to those of Figs. 10 and 12 is arrived at, the web of the transverse member 6 always being without any intersection.

The arrangement shown in Figs. 13 and 15 and effecting the joint between a longitudinal member 20 supporting the brake beam and an end transverse member 6 is also employed in the joint between such brake beam longitudinal member and the intermediate transverse member 26 (Figs. 16 to 18). The auxiliary partition 22 with reinforcing rib 22¹ again joins along longitudinal horizontal lines 23¹, 23² the flanges 26¹, 26² of the middle transverse member 26, which again ensures the suppression of any intersection on the web of such middle transverse member 26.

Figs. 19 to 22 illustrate the application of the invention to a support for the suspension springs. The cup 28 against which the shock absorber spring bears is offset relatively to the longitudinal member 1 of the frame and joined to such longitudinal member 1, on the one hand first by a small elbowed auxiliary partition 30 joining the flange 1¹ along a longitudinal horizontal line 31 and on the other hand by a second auxiliary partition 33 which also joins the flange 1¹ along the line of junction of such flange with the web of the longitudinal member 1. However, in this case because of the off-set of the cup 28 relatively to the longitudinal member 1, two very closely mutually adjacent ribs or brackets 32¹, 32² connect the cup 28 to the web of the longitudinal member 1.

Figs. 23 to 25 illustrate a support for a brake rod comprising two cheeks 40¹, 40² which carry the pivot bushing 41 for the rod and which join the end transverse member 6 of the frame through the intermediary

of a small auxiliary partition 42 which joins the flanges 10¹, 10² of such transverse member along longitudinal lines 43¹, 43², which avoids any transverse intersection.

Figs. 26 to 28 illustrate a support 45 for a balancing spring which is connected to the longitudinal member 1 by the intermediary of an auxiliary partition 50 joined to such longitudinal member along two horizontal lines 46¹, 46², which again avoids any transverse intersection on the longitudinal member.

The frame of Figs. 5 to 7 include also stop brackets 35 for suspension springs, these brackets being hollow and formed in casting with the longitudinal member 1 of the frame, as has been explained in detail with the aid of Figs. 3^b, 4^b and 5^b.

The frame also has (Figs. 29 to 31) a support 12 for a brake shoe suspension rod, formed on an intermediate transverse member 17 of the frame. This support comprises two ears 12¹, 12² formed in casting with a hollow body 13, itself formed in casting with a small longitudinal auxiliary partition 14. This auxiliary partition joins along longitudinal lines 15¹, 15² the flanges 17¹, 17² of the intermediate transverse member 17 of the frame. Thus in one entity is produced, on the one hand the arrangement according to Figs. 3^a and 4^a (small longitudinal auxiliary partition) and on the other hand the arrangement according to Figs. 3^b, 4^b and 5^b (hollow empty support). Thus in a quite complete manner any intersection on the web of the transverse member 17 and any risk of rents or cracks are avoided.

Claims:

1. A casting of large dimensions in which lugs are produced by casting with a longitudinal auxiliary partition of small dimensions joining flanges of the casting of large dimensions, the shrinkage of the metal of such longitudinal auxiliary partition being negligible and in consequence producing no cracks or rents.

2. A casting as set forth in claim 1, in which the small longitudinal auxiliary partition is completed by longitudinal cheeks, joined to the casting of large dimensions in such manner as to constitute a profile.

3. A casting as set forth in claim 1, in which the supports or other similar accessories formed with the casting are internally hollow, by suitable coring, enabling as far as possible the thicknesses to be rendered uniform and avoiding any intersection with the casting of large dimensions tending to rents or cracks.

4. A casting as set forth in claim 1, constituting a frame for railway rolling stock.

5. A casting constituting a frame for railway rolling stock, in which the supports for the suspension springs of the frame, the stop brackets for the suspension springs, the at-

tachment supports for the brake shoe suspension rods on end and intermediate trans-
verse members, the suspension supports for
the balancing springs, the suspension sup-
ports for the vertical rocking beams, the sup-
ports for the slides of the operating rod of
the vertical rocking beams or the transverse
member supporting the brake beams or sev-
eral of the elements are joined to the longi-
tudinal members or end transverse members
10 of the frame.

In testimony whereof I have affixed my
signature.

NESTOR LÉONARD.
